Filed Oct. 1, 1962, Ser. No. 71,928

Term of patent 14 years

(Cl. D64—11)

FIG. 3.

FIG. 4.

FIGURE 1 is a front perspective view of a calculating machine, showing our new design;

FIGURE 2 is a front elevational view thereof;

FIGURE 3 is a right side elevational view; and

FIGURE 4 is a rear elevational view thereof.

The dominant features of our design, which are shown in full-lines reside in the combination on the calculating machine disclosed of the particular hooded carriage which is shaped as shown.

We claim:

The ornamental design for a calculating machine, substantially as shown and described.
